UNITED STATES PATENT OFFICE.

CARLYLE E. HOOD, OF MEMPHIS, TENNESSEE.

FOUNTAIN-PEN.

1,338,629.

Specification of Letters Patent. Patented Apr. 27, 1920.

Application filed April 7, 1919. Serial No. 288,111.

To all whom it may concern:

Be it known that I, CARLYLE E. Hood, a citizen of the United States, residing at Memphis, in the county of Shelby and State 5 of Tennessee, have invented new and useful Improvements in Fountain-Pens, of which the following is a specification.

This invention relates to fountain pens and the principal object of the invention is 10 to provide a pen which will contain ink of different colors so that the same pen may be used with the different colored ink.

Another object of the invention is to provide means for cutting off the supply of one 15 color of ink while the other is being used.

The invention also consists in certain other features of construction and in the combination and arrangement of the several parts, to be hereinafter fully described, 20 illustrated in the accompanying drawings and specifically pointed out in the appended claims.

In describing my invention in detail, reference will be had to the accompanying 25 drawings wherein like characters denote like or corresponding parts throughout the several views, and in which:

Figure 1 is a sectional view of a pen constructed in accordance with my invention; 30 Fig. 2 is a view of the disk and its connecting rod;

Fig. 3 is a cross section on line 3—3 of Fig. 1;

Fig. 4 is a view of a detail.

Fig. 5 is a section on line 5—5 of Fig. 1.

In these views 1 indicates the holder which is provided with the two reservoirs 2 and 3 and with the central chamber 4. The reservoirs 2 and 3 are adapted to contain 40 ink of different colors while the chamber 4 is to receive a rod 5. This rod has secured to one end thereof a disk 6 which is provided at one side thereof with an opening 7. This opening is so located that it will

45 register with either one of the openings 2' and 3' in the bottoms of the reservoirs 2 and 3 when turned by the rod to come opposite the ends of said reservoirs. The edge of the disk engages an annular groove 8 formed in 50 the inner wall of the holder. The holder is provided with a removable end portion 9 which is connected with the main part of the holder by the screw-threaded sleeve 10. The said part 9 is provided with a pair of small

channels 11 and 12, the channel 11 forming a 55 continuation of the reservoir 2 and the channel 12 forming a continuation of the reservoir 3. These channels are separated by a partition 9' in the member 9. The inner end of this part 9 abuts against the outer 60 face of the disk 6 to hold the same with its edge in the groove 8. The outer ends of the channels 11 and 12 merge in the main channel 13 which leads to the penpoint 14. This penpoint is supplied with the usual 65 feeder 15. The end of the rod 5 passes through the rear end of the holder and is provided with a knob 16. A spring 17 is located in a recess 18 formed in the rear end 70 of the holder and bears against said knob to hold the disk 6 in firm engagement with the end of the main part of the holder so as to prevent leakage of the ink from the reservoirs. The holder is provided with a reduced threaded portion 19 at its rear end 75 and a threaded portion 20 on the extension 9 for receiving the usual cap 21.

It will thus be seen that by manipulating the knob the disk may be turned to open one or the other of the reservoirs to supply the 80 ink desired. The knob and the reduced part 19 may be provided with indicating marks to indicate when the opening 7 in the disk is registering with one or the other reservoir as shown at 7'.

To properly register the channels with the reservoirs I form a notch 22 in the holder to receive a projection 23 on the extension to properly position these two parts before the sleeve is screwed home.

It is thought from the foregoing description that the advantages and novel features of my invention will be readily apparent.

I desire it to be understood that I may make changes in the construction and in the 95 combination and arrangement of the several parts, provided that such changes fall within the scope of the appended claims.

What I claim is:

1. A fountain pen of the class described 100 comprising a holder having a pair of reservoirs therein, a penpoint carried by the holder, channels extending from said point to the reservoirs, a disk having an opening therein for controlling the connections of 105 the reservoirs with the channels, a rod passing through the holder and connected with the disk and means for turning the rod.

2. A fountain pen of the class described comprising a holder having a pair of reservoirs therein, an extension from the holder, having channels therein, means for remov-
5 ably securing the extension to the holder with the channels registering with the reservoirs, a penpoint carried by the extension,

a disk having an opening therein located between the holder and the extension and a rod passing through the holder and connected with the disk for rotating the same.

10 In testimony whereof I affix my signature.

CARLYLE E. HOOD.
